UNITED STATES PATENT OFFICE.

MILTON McCARTER, OF COLFAX, INDIANA.

FENCE-CLAMP.

1,109,172.

Specification of Letters Patent.

Patented Sept. 1, 1914.

Application filed March 23, 1914. Serial No. 826,692.

To all whom it may concern:

Be it known that I, MILTON McCARTER, a citizen of the United States, residing at Colfax, in the county of Clinton and State of Indiana, have invented a new and useful Fence-Clamp, of which the following is a specification.

The present invention appertains to fence clamps, and aims to provide a novel and improved contrivance of that nature.

It is the object of the present invention to provide a wire fence clamp of unique construction, whereby the same may be readily applied to and removed from the longitudinal strands of a wire fence.

The present invention contemplates the provision of a wire fence clamp embodying a series of peculiar coöperating jaws for receiving the fence wires or strands in a ready and effective manner, novel means being provided for moving the jaws into and out of clamping relation.

It is also within the scope of the present invention, to provide a wire fence clamp, which will be improved generally in construction, whereby the utility of the device will be enhanced, whereby the structure will be comparatively simple and inexpensive, as well as convenient, practical, serviceable and efficient in its use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawing, wherein:

Figure 1 is a front view of the improved fence clamp, portions being broken away. Fig. 2 is a back view of the clamp, portions being broken away. Figs. 3 and 4 are sectional views taken on the lines 3—3 and 4—4 respectively, of Fig. 2. Fig. 5 is a side elevation of the upper end portion of the clamp.

In carrying out the present invention, there is provided a frame, which is preferably in the form of a casing, and which comprises parallel bars 1, having spaced transverse webs or cross members 2 connecting

certain edges thereof. The frame or casting is of channel shape, certain portions of the back of the channel being cut away, to provide the spaced webs or cross pieces 2. 60 The edges of the webs 2 are preferably cut or molded on sinuous or tortuous lines to provide gripping jaws, it being noted that both edges of the webs 2 intermediate the upper and lower webs, are formed to provide jaws. The clamp further includes a second main part or element, in the form of a channel bar 3, which is slidably disposed between the bars 1 of the frame with its back resting against the inner sides or faces 65 of the webs 2. The back of the channel bar or part 3 is formed with transverse ribs or lugs 4, which are disposed between the webs or jaw members 2. The channel member 3 is preferably in the form of a casting and the edges of the ribs or lugs 4 are cut or 70 molded on sinuous lines corresponding or matching with the edges or jaw portions of the webs 2. Both edges of each rib 4 are sinuous or tortuous to provide opposed jaws 75 coöperable with the adjacent jaws of the adjacent webs, whereby the jaws of the webs and the ribs may be made to coöperate upon both the upward and downward movements of the channel member or slide 3 with respect to the frame.

The channel member or slide 3 is maintained in place within the frame, by means of a retaining plate 5 secured, by means of screws or otherwise, to the free edges of the bars 1 intermediate the ends of the said bars, and engaging the free edges of the flanges of the channel member 3. It is evident that the plate or retaining member 5 holds the channel member or slide 3 snugly 80 within the frame, but permits the channel member to be readily slid longitudinally with respect to the frame. A cap 6 fits over the upper end of the frame, or the bars 1 thereof, the cap 6 being divided from one 85 side of the frame, to the other, to provide two sections 7, the sections being secured to the upper ends of the bars 1, by means of bolts or other securing elements 8 passed through the side portions of the cap sections 90 7 of the upper end portions of the said bars. The front and rear cap sections 7 are provided with an opening 9 between their adjoining edges, and the shank of a screw 10 is journaled through the opening 9, the 105 said shank and screw being provided with collars or shoulders 11 seating against or

contacting with the upper and lower faces of the cap 6, to permit the screw 10 to rotate, and to prevent its longitudinal movement with respect to the frame. The upper end portion of the screw 10 is formed with a wrench-engaging portion 12, whereby the screw may be properly rotated by means of a suitable wrench, although it is to be understood that the screw may be actuated in any suitable manner.

The screw 10 is utilized for actuating the channel member or slide 3, the upper end portion of the channel member 3 being provided with a solid portion 13 between its flanges, which portion 13 is provided with a longitudinal bore 14 loosely receiving the threaded portion of the screw 10. The solid portion 13 of the channel member 3 is also provided with a transverse rearwardly opening socket or recess 15 in which is snugly fitted a nut 16 through which the screw 10 is threaded. The nut 16 is held non-rotatably within the socket or recess 15, and in receiving the lower or inner end portion of the screw 10, will enable the channel member 3 to be reciprocated or actuated longitudinally, by rotating the screw 10.

As a means for attaching the clamp to a stretching mechanism, which may be of any suitable character, a pair of open or slotted links 17 are slidable through slots 18 formed in the side bars 1, and complementing slots 19 formed in the flanges of the channel member 3. The slots 19 are elongated in order to enable the channel member 3 to be moved longitudinally, without interference. The links 17 are disposed transversely of the clamp and arranged adjacent the ends thereof, the ends of the links protruding beyond the bars 1, and the links being provided with bulged or enlarged portions 20 adjacent certain ends, while retaining rings or elements 21 are engaged through the other ends of the links. The rings 21 are arranged to strike or seat against the corresponding side bar 1, to lock the links against withdrawal, when the chain sections 22 are engaged to the other ends of the links so as to enable the clamp to be connected to the stretching mechanism. The chain sections 22 may be readily passed through the bulged or enlarged portions 20 of the links, whereby when the chain sections are tightened, the links may be locked with the corresponding end portions of the links, as seen in Figs. 1 and 4, to thereby effectively connect the chain sections with the clamp. It is obvious that the chains 22 may be readily applied to and disengaged from the links 17, and may be adjusted readily with respect to the links. It is also apparent that when the chains 22 are disengaged from the links 17, the links may be withdrawn from the slots 18 and 19, and may be reversed, if desired. The enlarged or bulged portions 20

of the links are arranged to snap through the slots 18 of the bars 1 and therefore, when the links are applied, the bulged portions 20 will normally prevent the withdrawal of the links, unless the links are 70 forcibly extracted from the clamp 3.

As a matter of further improvement, the clamp is provided with upper and lower clamps 23 and 24, respectively, for clamping the upper and lower strands of a wire 75 fence, which are usually of larger gage than the intermediate strands or wire. The upper clamp 23 is adjustable, and comprises a U-shaped bolt 25 straddling the rear edges and sides of the bars 1, and a pair of cross bars or jaws 26 having their ends loosely embracing or engaging the end portions of the bolt 25. Nuts 27 are threaded upon the ends of the bolt 25 to clamp the jaws 26 together, and to clamp the frame between the bolt 25 and the jaws 26. It is evident that when the nuts 27 are loosened, the clamp 23 may be adjusted longitudinally upon the upper end portion of the frame, and when the nuts are tightened, the clamp 90 23 will be locked in its adjusted position, and the jaws or clamping bars 26 will be clamped together. The lower clamp 24 is stationary, inasmuch as the lower strand or wire of the fence can in all cases be accommodated thereby; the lower clamp 24 embodying a clamping plate or jaw 28 co-operating with the lower web 2 of the frame and adapted to be clamped thereagainst by a bolt 29 engaged through the lower end 100 portion of the frame and the clamping plate or jaw 28.

In the use of the present clamp, the fence wires or strands 30 may be readily applied thereto, by simply rotating the screw 10 properly, through the medium of a wrench or other suitable implement, so that the jaws 4 will be spaced from the jaws 2, which will enable the strands or wires 30 to be readily placed between the respective jaws. 110 In practice, it is preferable to provide the clamp with a sufficient number of co-operating jaws 2 and 4, to enable the clamp to accommodate various woven wire fences. Then, by rotating the screw 10 properly, the jaws 2 and 4 may be brought into mutual gripping relation, to tightly grip the wires 30 between the sinuous or tortuous faces of the jaws, whereby when the clamp is drawn or pulled through the medium of 115 the stretching mechanism (not shown) attached to the chains 22, there will be no liability of the wires 30 pulling loose, even though the clamp is subjected to severe strains when long and heavy fences are being stretched taut.

A salient feature of the present invention resides in the fact that the channel member or slide 3 may be moved either upwardly or downwardly, to bring the jaws 2 and 4 120

into gripping relation, it being noted that both the upper and lower edges of the said jaws are provided with coöperating jaw faces. The operative connection of the 5 screw 10 with the upper end of the frame and with the upper end of the channel or slide 3 thus enables the said channel member or slide to be actuated in both directions.

When the upper and lower wires or 10 strands of the fence are of larger gage than the intermediate wires or strands, the clamps 23 and 24 may be employed for gripping the same. Thus, the lower wire or strand 31 may be clamped or gripped between the 15 lower end portion of the clamp frame of the clamp plate 28 as clearly suggested in Fig. 1, while the upper wire or strand 32 may be readily clamped between the edge portions of the clamping or jaw bars 26 20 after the nuts 27 have been loosened, and the clamp 23 properly adjusted upon the upper end portion of the frame. If, however, the upper and lower strands are of the same gage as the intermediate strands 25 or wires, the clamping devices 23 and 24 need not be employed.

The several parts of the present device may be readily manufactured and assembled, and may be quickly and easily taken 30 apart for the purpose of repair or replacement.

From the foregoing, taken in connection with the drawings, the salient features and advantages of the present device will be obvious to those versed in the art without further comment being necessary, it being noted that the objects aimed at have been carried out satisfactorily by the provision 35 of the structure herein disclosed.

Having thus described the invention, what 40 is claimed as new is:—

1. In a clamping device, a channel-shaped bar having its back cut away to provide spaced webs, a second channel-shaped bar 45 fitted within the aforesaid bar with its back resting against the said webs, the back of

the second bar being provided with transverse ribs between and coöperable with the said webs, means carried by the flanges of the 50 first bar and engaging the flanges of the second bar to hold the second bar slidably within the first bar, and actuating means connecting certain ends of the bars for sliding the second bar.

2. In a clamping device, a frame having 55 a series of jaws, a slide carried by the frame and having a series of jaws coöperable with the aforesaid jaws, means connecting the frame and slide for actuating the latter, and an adjustable clamp mounted upon one 60 end portion of the frame, the adjustable clamp including a U-shaped bolt straddling the frame, coöperable clamp bars mounted upon the end portions of the said bolt, and nuts threaded upon the ends of the bolt. 65

3. In a clamping device, a frame having 70 a series of jaws, a slide mounted within the frame and having jaws coöperable with the aforesaid jaws, a cap mounted upon one end of the frame, a screw journaled through the cap and having means for engaging the cap to prevent the longitudinal movement of the screw, and a nut portion carried by one end of the slide and threadedly receiving the said screw. 75

4. In a clamping device, a frame having transverse slots, clamping means carried by the frame, open links fitting through the said slots, each link having a bulged portion adjacent one end for the passage of 80 chain links therethrough to engage within the said end, and retaining means carried by the other ends of the links and seatable against the frame.

In testimony that I claim the foregoing 85 as my own, I have hereto affixed my signature in the presence of two witnesses.

MILTON McCARTER.
